(57) **CLAIM**

The ornamental design for a cell phone, as shown and described.

DESCRIPTION

FIG. 1 is a front perspective view of a cell phone;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top elevational view thereof;

FIG. 7 is a bottom elevational view thereof; and,

FIG. 8 is a front elevational view of the cell phone design in its intended environment.

The environmental subject matter shown in broken lines in FIG. 8 is for illustrative purposes only and form no part of the claimed design.
